UNITED STATES PATENT OFFICE.

WOODBURN LANGMUIR, OF NEW YORK, N. Y.

DESIGN FOR A CARRIAGE TIRE AND RIM.

SPECIFICATION forming part of Design No. 34,802, dated July 16, 1901.

Application filed June 19, 1899. Serial No. 721,143. Term of patent 7 years.

To all whom it may concern:

Be it known that I, WOODBURN LANGMUIR, a subject of the Queen of Great Britain, and a resident of New York, in the county of New York and State of New York, have invented a certain new and useful Design for a Carriage Tire and Rim, of which the following is a specification.

The drawings show in Figure 1 a cross-section of the tire and rim, and in Fig. 2 a perspective view of the same.

As shown in the drawings, the leading or material features of my design consist of the wearing portion C, the top of which is semi-circular in shape, the sides D of said wearing-surface forming an acute angle with the base E, on which it rests, the sides of the flange

flaring outward, so as to leave a V or wedge shaped space B between the flange A and the inwardly-inclined sides D, the sides of the tire 20 in no wise conforming to those of the flange.

Having described my invention, what I claim as new, and desire to secure by Letters Patent, is—

The design for a carriage tire and rim, substantially as herein shown and described.

Signed at New York, in the county of New York and State of New York, this 14th day of June, A. D. 1899.

WOODBURN LANGMUIR.
